UNITED STATES PATENT OFFICE.

ALONZO S. BLOWERS, OF PORTLAND, INDIANA.

ELECTRIC HOIST.

1,082,398.

Specification of Letters Patent.

Patented Dec. 23, 1913.

Application filed September 19, 1910. Serial No. 532,597.

To all whom it may concern:

Be it known that I, ALONZO S. BLOWERS, a citizen of the United States, residing in the city of Portland, in the county of Jay 5 and State of Indiana, have invented certain new and useful Improvements in Electric Hoists, of which the following is a full, clear, and accurate specification and exposition, being such as will enable others to 10 make and use the same with absolute exactitude.

This invention is intended particularly as a device for elevating material in the construction of buildings, wherein two cars are 15 provided which are oppositely disposed as to their movements up and down.

The object of my present invention, broadly speaking, is to provide a hoist which will be strong and durable in construction, easily operated and controlled, 20 easily assembled temporarily in position and easily taken down, and which can be made and sold at a comparative low price.

Another object is to provide an electric 25 hoist adapted to transfer material both up and down at the same time, one car going upward as the other car goes downward, usually one car being loaded while the other is empty, all being under the control of a 30 single operator.

Other objects and particular advantages 35 of my invention will be brought out in the course of the following description, will be shown in the accompanying three sheets of drawings, and will be correlated in the appended claim.

The preferred manner for carrying out 40 the objects of my invention is shown in the accompanying drawings, in which—

Figure 1 shows my invention complete as 45 in front elevation. Fig. 2 is a plan, partly in section as taken on line 2—2 of Fig. 1. Fig. 3 is a side elevation, showing certain features of the invention. And Fig. 4 is a detail plan view of the top of the construction.

Similar indices denote like parts throughout the several views of the three sheets of drawings.

In order that the construction and the 50 operation of my invention may be more fully understood and comprehended I will now take up a detail description thereof in which I will set forth the invention as briefly and as comprehensively as I may.

In the drawings letter A denotes the

ground line; B denotes the joists of the second floor; and C denotes the joist of the third floor or the roof.

Whenever it is desired to place the hoist 60 the joists which might be in the way are removed in order to provide an opening between the joists of sufficient size.

Numerals 1 and 2 denote the two side- 65 posts, and 3 denotes the center post. Said posts are set up vertically resting on the sill 4 which is laid on the ground A, or upon a platform, or upon joists, as desired. The posts are secured in vertical position as shown, extending up beyond the joist C 70 through the derrick hereinafter referred to.

Mounted on top of the upper joists is a derrick comprising the four corner posts 5, 6, 7 and 8. Posts 5 and 6 are disposed at an angle with relation to each other, tapering 75 upward, and they are connected by the crossing braces 9 and 10 which are arranged as shown in Fig. 3. The other two posts, 7 and 8, are arranged in the same manner 80 with relation to each other, but they are arranged parallel with relation to posts 5 and 6, as indicated in Fig. 1. Posts 5 and 6 are connected at the top by the tie 11, and posts 7 and 8 are likewise connected by the tie 12.

Resting across on ties 11 and 12 are the 85 four cross-ties 13, 13', 13'' and 13''. Disposed across on top of the said cross-ties are the two pulley-devices 14 and 15 each consisting of two flat members spaced a short distance apart and having two pulleys a and b and c and d, respectively, journaled therebetween as shown. Pulley b is located directly over the center between posts 1 and 3, and pulley d is located directly over the center between posts 2 and 3. 95 For the purpose hereinafter made apparent the pulleys a and c are located nearer together than are the pulleys b and d, this being accomplished by locating the forward ends of members 14 and 15 closer together 100 than are the other ends thereof.

A car is adapted to operate up and down between the posts 1 and 3. Said car comprises a base or floor 20. Extending up from the center of each side of the base are 105 the vertically disposed side members 21 and 21'. The side members are connected to the corners of the car each by two angularly disposed braces 22 extending from member 21 and braces 23 extending in like manner 110 from member 21', all as indicated in Fig. 3. Members 21 and 21' are connected at their

upper ends by a cross-bar 24. Braces 25 and 26 extend from near the center of cross-bar 24 at an angle and with their lower ends secured to the members 21 and 21', respectively, as shown in Fig. 1, which completes the left-hand car.

The right-hand car is the same in every particular as the above, same having the base or floor 30, the side-members 31 and 31', the braces 32 extending from member 31, and braces 33 extending from member 31', also it is provided with the cross-bar 34 connecting the upper ends of members 31 and 31', and braces 35 and 36 extending from near the center of brace 34 at an angle with their lower ends secured to members 31 and 31', respectively.

Secured in the center of the inner face of post 1 is a guide-strip D which extends from end to end thereof. In like manner secured opposite to guide-strip D, on the left-hand face of post 3, is the guide-strip E. On the opposite face of post 3 is secured the guide-strip F, and opposite thereto on the inner face of post 2 is secured guide-strip G.

Secured to each of the members 21, 21', 31 and 31' are guide-blocks, two at the top and two at the bottom of each, the guide blocks for each of said members being denoted by letters H, I, J and K, respectively.

From the above it is apparent that the two cars are adapted to slide up and down by which the floors thereof may be brought even with the top of the joists of either set 35 of joists or to any other point therebetween as desired.

Numeral 40 denotes a platform (Fig. 2) which should be rigidly connected to the ground or on the top of the joists B whereby 40 it may not be easily lifted when in operation as presently described, or if desired the posts 1, 2 and 3 may also rest on said platform as indicated in Fig. 1 which will help to retain the said platform in position. Mounted on 45 said platform are two pedestal hangers 41 and 42 in which is revolvably mounted the shaft 43. Secured on shaft 43 is the drum 44 which is coaxial therewith. The ends of 50 said drum terminate in the heads 44^a and 44^b which are integral and coaxial with said drum and they are larger in diameter than is the drum 44. Of larger diameter than said heads and secured on the ends thereof are the respective flanges 45 and 45', same 55 being coaxial with said shaft 43, all substantially as indicated.

Numeral 50 denotes a cable or the like: one end of said cable is secured around the center of the cross-bar 24, of the left-hand 60 car, where it is secured by a clamp 51, from which it extends upward over pulley b, then over pulley a, then downward to the drum 44. After encircling the drum with several convolutions the cable again extends upward, 65 passing over pulley c, then over pulley d,

and then downward to cross-bar 34 of the right-hand car, where it is secured by the clamp 52. Also mounted on shaft 43 is the large band-wheel 53. Located in alinement with band-wheel 53 and in the rear thereof 70 is the small band-wheel 54, same being carried by shaft 55. Also carried on shaft 55 is the band-wheel 56. Said shaft 55 is supported revolvably by the two pedestal hangers 57 and 58 which extend up from platform 40. Connecting band-wheels 53 and 54 is a belt 59.

Numeral 60 denotes an electric motor which must be capable of operating either forward or backward.

Numeral 61 denotes the motor pulley or band-wheel. Connecting the band-wheel 56 and the band-wheel 61 is a belt 62.

By the above it is seen that the motor may operate at a very high rate of speed, transmitting power through the several wheels and belts to the drum, which latter will revolve at a much slower rate of speed but at a speed of the desired sufficiency.

Numeral 63 denotes a stand located above 90 and supported by the platform 40. Located on the left-hand end of the stand 63 is the operator's seat 64.

The brake mechanism comprises the segmental member 65 secured to block 66, the latter being supported on the platform 40. In the periphery of member 65 are square notches in which may engage the end of the plunger 67. Said plunger is adapted to slide up and down against the arm 68, parallel therewith, which latter is pivoted at its lower end and is adapted to be moved forward and backward, there being a handle on its upper end which will be within reach of the operator on the seat 64. The plunger 67 is normally retained downward in engagement with said notches of member 65 by a helical spring 69. A rod 70 extends from the plunger 67 up the arm 68 where it is connected to the small lever 71 which latter is 105 pivoted to the arm 68 whereby when said lever is moved toward the handle it will raise the plunger 67 against the resiliency of said spring thereby allowing the arm 68 to be moved forward or backward. Connected to 110 the arm 68 is a band 72 which passes over the head 44^a and then downward and rearward and with its other end secured to the platform 40. A brake-shoe 73 is secured to the inner face of band 72 which is adapted to 115 contact with the periphery of the head 44^a.

From the above it is apparent that by moving the arm 68 rearward that the shoe 73 will be tightened against the head 44^a thereby locking the drum, or if the arm 68 120 be moved forward then the drum will be released from the shoe. The arm 68 may be locked in any position as desired.

Mounted on the stand 63, at the side of seat 64, is a double-switch, comprising the 125

base 80 having nine contacts denoted by numerals 81, 82, 83, 84, 85, 86, 87, 88 and 89, which are arranged in three rows of three each, substantially as indicated in Fig. 2. To the three middle contacts, 81, 82 and 83 is pivoted the handle 90 which is at all times connected with the three last mentioned contacts, and it is adapted to be turned over to the right connecting it also with contacts 87, 88 and 89, or in place of the latter it may be turned over to the left connecting it with contacts 84, 85 and 86.

Letters L, M and N denote the three service wires which conduct the electric current from the source of supply. Said service wires are connected to contacts 81, 82 and 83, respectively. Three wires O, P and Q lead into the motor, the other ends of the last named wires are connected as follows: Wire O connects with contacts 88 and 86; wire P connects with intermediate wire R; and wire Q connects with intermediate wire S. Intermediate wire R connects the two contacts 85 and 89, and intermediate wire S connects the two contacts 87 and 84.

From the above it will be apparent that I provide a reversing switch, that is to say—when the handle 90 is not connected with either the right or the left hand sets of contacts then no current can enter the motor and therefore it will not operate. If, however, handle 90 be turned to the right so that it will engage contacts 87, 88 and 89 then the motor will operate in one direction thereby causing the drum to revolve causing one of the cars to be raised and at the same time lowering the other car. Now should the handle 90 be thrown over to the left engaging it with contacts 84, 85 and 86 then the electric current will operate the motor in the opposite direction which, manifestly, will reverse the movements of the cars up and down.

In practice the invention is to be used, primarily, in elevating brick, mortar, or other material usually moved in wheelbarrows and the loaded wheel barrow may be run onto the car which may be down on the ground line A, at which time the other car will be at the highest point of elevation. Now the operator will release the brake and throw the handle 90 over to start the motor thereby causing the load to be elevated, and at the same time the other car will be lowered to receive its load. When the first car reaches its highest point then lever 90 is moved to the center cutting off the current, at same time the brake is applied to hold the cars when desired. While the loaded wheelbarrow is being run off of the car last elevated another loaded wheelbarrow may be

run onto the car which has just been lowered, after which the operator will then throw the switch to operate the motor in the opposite direction from that which it was last operated which will cause the cars to again change their positions. As the building increases in height the device may be changed accordingly: After another set of joists have been positioned above the joists C then the derrick should be moved to position on top of the last placed joists, and at same time the platform 40 and the mechanisms carried thereon may be moved on up to rest on top of joists B.

All of the several parts are adapted to be taken apart in sections suitable for handling and for transportation, and adapted to be again assembled in similar positions.

In order to adjust the invention to the several floors or to additional floors, or to a less number of floors or sets of joists, the cable may be made longer or shorter as desired, or it may be given a greater or a less number of convolutions around the drum.

I desire that it be fully understood that various changes may be made in the several details of construction without departing from the spirit of my invention or of sacrificing any of the advantages thereof.

Having now fully shown and described my invention and the best exemplification thereof to me known at this time, what I claim and desire to secure by Letters Patent of the United States, is—

In a hoist, the combination with a plurality of horizontal joists and a series of guide posts arranged vertically thereof and extending up beyond said joists; of a derrick mounted on the upper tier of joists and comprising a series of corner posts mounted in upwardly convergent relation, top and bottom tie rails connecting the respective pairs of posts last mentioned, cross-ties connecting the top rails, a pair of slotted frames horizontally mounted on the ties in convergent relation and carrying spaced pulleys therein, oppositely movable cars mounted in the first mentioned posts, a cable attached to each car and passed horizontally over the pulleys of the frames thereabove toward the convergent ends and a reversible motor mechanism having a drum upon which said cables are oppositely wound to operate the cars.

In testimony whereof I have hereunto subscribed my name in the presence of two subscribing witnesses.

ALONZO S. BLOWERS.
